UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL CASTING-MACHINE.

1,157,785.

Specification of Letters Patent.

Patented Oct. 26, 1915.

Application filed May 1, 1913. Serial No. 764,744.

To all whom it may concern:

Be it known that I, DAVID S. KENNEDY, a citizen of the United States, residing at Brooklyn, in the county of Kings and State 5 of New York, have invented certain new and useful Improvements in Typographical Casting-Machines, of which the following is a specification, reference being had therein to the accompanying drawing.

10 My invention relates to typographical casting machines, such for instance as linotype machines of the general character represented in Letters Patent of the United States, No. 436,532, to O. Mergenthaler, 15 wherein a composed line of matrices is presented momentarily to the face of a slotted mold in order to form type characters on the edge of a printing slug cast therein. When these machines are operated under certain 20 conditions, the molds become unduly heated by the molten type metal delivered thereto, and means are therefore provided to regulate their temperature within the proper limits by the use of cold water or other cooling mediums, as set forth in my previous 25 Letters Patent, No. 959,755, May 31, 1910. In the specific construction illustrated in the said patent, the mold disk is mounted to rotate about a hollow stud, to which the water 30 or other cooling fluid is supplied through suitable piping. Ordinarily, this piping connects with the customary source of water supply, or the water is forced therethrough by a pump from a reservoir. In the present 35 instance I preferably employ a closed and continuous system including a reservoir, and rely for circulation upon the thermic currents induced by the heat of the mold. In such machines, also, the mold carrier is 40 mounted on a reciprocating slide, and as the reservoir is stationary, I have devised means to permit this relative movement without the interruption of the piping, or the danger of its disconnection and the leakage resulting therefrom. To this latter end I provide the piping with flexible or extensible members at suitable points, and in this way permit the said relative movement.

45 In the accompanying drawing, I have illustrated my invention in preferred form and by way of example, and as adapted to the ordinary linotype casting mechanism. However, many variations and alterations may be made therein, and in its mode of application, which will still be comprised with-

in its spirit. Generally speaking, I desire it to be understood that I do not limit myself to any specific form or embodiment, except in so far as such limitations are specified in the claims.

60 The drawing is a perspective view, partly in section, of a portion of the casting mechanism, having my improvements embodied therein.

65 As set forth in my previous Letters Patent, the mold wheel or carrier A is equipped with the slotted mold B and is mounted upon the reciprocating mold slide C, in such manner that the mold may be moved laterally toward and from the composed line, not 70 shown herein. Also as in said Letters Patent, the carrier A is arranged to rotate about the large, hollow stud E, through which water or other equivalent cooling medium is 75 caused to circulate from the pipe system F, F'.

75 In the present instance, the pipes F, F' are stationary and lead respectively from and to the reservoir G, which is also stationary, and is mounted in any desired manner, 80 preferably within the column or base frame G' of the machine. The hollow stud E is provided with the inlet and outlet tubes H and H', which necessarily partake of the reciprocating movements of the mold slide 85 C. The tubes H and H' are respectively connected to the stationary pipe branches F and F' by the flexible members J and J'. This yielding or flexible connection permits the relative movement of the mold carrier C 90 and the hollow stud E, with reference to the stationary reservoir and piping, without the danger of interruption or breakage, and the consequent leakage of the cooling medium 95 so disadvantageous in connection with high temperatures and apparatus of this description. Also, as above indicated, the chambers in the stud E, the tubes H, H', the members J, J', the pipes F, F', and the reservoir G, constitute a closed and continuous 100 system, wherein the circulation is secured through the thermic currents induced by the high temperature of the mold B.

105 As previously stated, I have shown my invention in preferred form and by way of example, but many variations may be made therein without departure from its scope. Thus, the points of application of the yielding or flexible connections may be varied, or other equivalent devices, such as sliding 110

joints, or the like, may be substituted therefor. Or the arrangement and location of the elements of the closed system may be suitably changed. These and other modifications will suggest themselves to those skilled in the art.

Having thus described my invention, its construction and mode of operation, what I claim and desire to secure by Letters Patent 10 of the United States, is as follows:

1. In a typographical casting machine, the combination of a mold adapted to contain molten metal, and means for cooling the mold and its contents to prevent overheating thereof due to the successive casting operations, said cooling means including a tank or reservoir to contain the cooling medium, a cooling chamber, and a pipe system connecting the cooling chamber and reservoir so that the cooling medium may circulate freely back and forth between the two, and the said cooling chamber being arranged in proximity to the mold and within the heating zone of the molten metal therein so

that the heat thereof will effect and control 25 the circulation of the cooling medium which, in turn, maintains the mold and its contents at a uniform temperature.

2. In a typographical casting machine, the combination of a mold mounted to reciprocate to and from casting position, a closed cooling chamber arranged in proximity to the mold and reciprocable therewith, a stationary closed tank or reservoir for the cooling medium, and a pipe system connecting the reservoir with the cooling chamber so that the cooling medium may flow back and forth therebetween under the influence of the heat from the mold, the said pipe system comprising sections which are flexibly 30 connected to permit the reciprocating movement of the cooling chamber with the mold.

In testimony whereof I have affixed my signature in presence of two witnesses.

DAVID S. KENNEDY.
